UNITED STATES PATENT OFFICE

GUSTAF I. JOHNSON, OF MALDEN, MASSACHUSETTS

FLASH LIGHT

Application filed January 23, 1928. Serial No. 248,603.

The present invention relates in general to improvements in the art of producing artificial light, and relates more specifically to improvements in the construction and operation of magneto actuated electric flash lights wherein the electric current generating mechanism is manipulable by hand and the use of batteries is thereby dispensed with.

An object of the invention is to provide an improved electric flash light of the magneto actuated type, which is extremely simple and compact in construction, and which is conveniently manipulable to produce a relatively uniform and bright light. Another object of the invention is to provide improvements in magneto structures especially adapted for installation within a flash light handle, and mechanism for conveniently manipulating and for effecting desired adjustment of the elements of such structures. A further object of the invention is to provide an improved flash light handle for magneto actuated devices of this kind, wherein the handle is readily removable to permit inspection of the magneto and of other mechanism disposed within the handle, and wherein the housing handle presents a perfect grip as well as an extremely pleasing appearance. Still another object of the invention is to provide a mechanically actuated electric flash light all elements of which may be manufactured at minimum cost with the aid of punches and dies, and which may be quickly assembled and dismantled with ordinary tools. These and other objects of the invention and advantages gained with the present improvement, will be apparent from the following description.

A clear conception of an embodiment of the invention and of the mode of manufacturing, assembling and manipulating devices constructed in accordance therewith, may be had by referring to the drawing accompanying and forming a part of this specification in which like reference characters designate the same or similar parts in the various views.

Fig. 1 is a longitudinal section through parts of the handle, frame and other elements of an improved magneto actuated flash light.

Fig. 2 is a part sectional side view of the

improved magneto actuated flash light with one section of the handle casing removed, showing the armature actuating handle moved inwardly against the casing.

Fig. 3 is a fragmentary side view of the improved magneto actuated flash light with one section of the handle casing removed, showing the armature actuating handle swung outwardly to its extreme position.

Fig. 4 is a rear end view of the improved flash light showing the handle casing assembled.

Fig. 5 is a full side view of one of the frame sections showing cross-sections through the pins and shafts associated therewith.

Fig. 6 is a full side view of the other frame section showing cross-sections through the pins and shafts associated therewith.

Fig. 7 is a side elevation of the one way automatic motion transmitting clutch associated with the armature shaft.

Fig. 8 is an end view of the one way automatic motion transmitting clutch.

The magneto actuated manually operable flash light specifically illustrated in the drawing comprises in general an adjustable reflector portion 2 of ordinary construction having a lens and a light bulb 3 associated therewith; a frame consisting of detachably interconnected side plates 11, 12 secured to a front supporting bracket 23 rigidly attached to the reflector portion 2; a magneto mounted between the side plates 11, 12 of the frame remote from the reflector 2; manually manipulable actuating mechanism associated with the frame between the magneto and the reflector portion 2; and a sectional casing 4 providing a complete enclosure for the frame and the magneto, as well as the gearing of the actuating mechanism.

The front supporting bracket 23 of the frame is preferably formed of sheet metal, and may be rigidly attached to the shell of the reflector portion in any suitable manner. The bracket 23 is provided with a pair of integral rearwardly projecting ears 24 to which the side plates 11, 12 are detachably secured by means of screws 40. The side plates 11, 12 which extend longitudinally away from the bracket 23, are likewise preferably

formed of sheet metal, being shaped as shown in Figs. 5 and 6. The side plate 11 is merely a flat punching having no lateral projections thereon, but the side plate 12 may be provided with an integral inwardly extending stop lug 35 the purpose of which will be later explained.

The improved magneto comprises a four pole rotary permanent magnet 5 revolvable between two sections of a fixed armature secured to the side frame 11. The rotary magnet 5 is composed of a sufficient number of laminations or plates to produce the desired fly-wheel effect necessary to insure uniform rotation thereof, these plates being stamped from sheet metal and rigidly attached to a supporting shaft which is mounted in bearings in the side frames 11, 12. The poles of the rotary magnet 5 may be separated by radial gaps formed as shown, and the rotor has maximum diameter permissible within the casing 4. The rear section of the fixed armature is located at the extreme rear end of the handle and comprises a laminated metal core 6 secured to the side frame 11 by means of retaining bolts 31 cooperating with elongated openings 32 in the laminations, and a wire winding or coil 8 embracing the core 6. The front section of the fixed armature is located between the magnet 5 and the reflector portion 2 and comprises a laminated core 7 secured to the side frame 11 by means of retaining bolts 42 likewise cooperating with elongated openings in the laminations, and a wire winding or coil 9 embracing the core 7. Each of the cores 6, 7 presents a pair of pole pieces to the revolving pole faces of the magnet 5, through adjustable air gaps the width of which may be varied as desired by virtue of the elongated openings 32 provided in the core laminations. The armature coils 8, 9 are interconnected by means of a conductor 36, and the front coil 9 is connected to the lamp bulb 3 by means of a connection 34. The rear coil 8 is further grounded on the frame plate 11 by means of a connection 38, and suitable insulation is provided wherever necessary or desirable.

The manually manipulable actuating mechanism comprises a rearwardly extending oscillatory operating lever 13 disposed outside of the casing 4, and a train of gearing connecting the lever 13 with the rotary magnet 5. The lever 13 which may be pressed from sheet metal or otherwise constructed, is formed integral with a toothed segment 16. The segment 16 is pivotally supported upon a pivot pin 14 associated with the side frames 11, 12, and is provided with an integral lateral projection 25 which is engageable with the stop lug 35 of the side frame 12 as shown in Fig. 3, in order to limit the outward movement of the lever 13. A coil spring 15 which embraces the pivot pin 14, has one end connected to the side plate 11 and has its oppo-

site end disposed to press against the segment 16 and adapted to constantly urge the segment 16 and hence the lever 13, outwardly with respect to the casing 4. The teeth of the segment 16 coact with a pinion 17 which is rigidly attached to a gear 18, the combined gear and pinion being rotatably supported upon a pivot 39 secured to the side plate 12. The gear 18 meshes with another pinion 19 loosely mounted upon the magnet shaft 10, and having the pawl actuating plate 27 of a clutch 20 secured thereto. The one-way clutch 20 shown in detail in Figs. 7 and 8, is composed of a circular side plate 26 frictionally associated with the shaft 10 and providing a pivotal support for a pawl 29, and a ratchet wheel 30 rigidly attached to the magnet shaft 10 and located between the plates 26, 27. The outer end 28 of the pawl 29 is provided with a slot which is engaged by a pin projecting laterally from the plate 27, the arrangement of elements being such that when the plate 27 is rotated relatively to the plate 26, in a clockwise direction as viewed in Fig. 7, the pawl 29 is placed into positive engagement with the teeth of the ratchet wheel 30 and thereby positively transmits rotary motion to the shaft 10, whereas during reversal of the motion, the pawl 29 is swung outwardly thereby disengaging the ratchet wheel 30 and permitting continued unrestrained movement of the rotary magnet 5 in the same direction as when driving force is being applied.

The side frames 11, 12 beside providing supports for the magneto and the gearing, are detachably connected and definitely spaced apart by means of pins 41, 21. The pin 41 is located at the forward portion of the frame and the clamping nuts associated therewith are disposed entirely within the casing 4. The pin 21 is located at the extreme rear end of the frame and has ends which penetrate the sections of the casing 4. The sections of the casing 4 are formed of pressed metal and coact with each other along a plane disposed longitudinally of the handle and perpendicular relative to the axis of rotation of the magnet 5, and are shaped to present a perfect grip to the hand of an operator. The forward portions of the casing sections are formed to snugly coact with a rearwardly extending flange 33 of the reflector portion 2, and a single set of clamping nuts 22 coacting with the protruding ends of the pin 21 serve to clamp the casing sections in assembled position.

During normal operation of the improved flash light, the parts having been properly assembled as shown, the operator holds the handle casing 4 in the palm of his hand and oscillates his fingers to successively apply inward pressure to the lever 13 in relatively rapid succession. When the lever 13 is moved inwardly toward the handle, the seg-

ment 16 carried thereby imparts rotary motion to the pinion 17 and gear 18 from whence the rotary motion is imparted to the pinion 19 and the clutch 20 causing the clutch to positively rotate the magnet 5 in a clockwise direction as viewed in Figs. 2 and 3. The revolving magnet 5 cooperates with the fixed armature in a well known manner to generate electric current which acts through the connections 34, 36, 38 and the metal frame to light the lamp bulb 3. When the inward pressure upon the lever 13 is released, the coil spring 15 immediately becomes effective to move the segment 16 and the lever 13 outwardly, this motion continuing if unrestrained, until the projection 25 on the segment 16 engages the stop 35 on the frame 12. During this outward movement of the lever 13, the direction of rotation of the gearing 20 is reversed, but the direction of rotation of the magnet 5 is not affected. Upon reversal of the loose pinion 19, the pawl 29 is immediately withdrawn from the ratchet 30 thereby permitting the magnet 5 to continue in its rotation by virtue of the inertia. As soon as the lever 13 has reached its extreme outermost position, it should again be brought inwardly against the handle by the operator, thereby again applying positive rotation to the permanent magnet 5. In this manner, the magnet 5 may be readily rotated at relatively uniform speed thereby generating relatively constant electric current and maintaining a relatively uniform and bright light.

By locating the armature poles 6, 7 and coils 8, 9 on opposite sides of the magnet 5 along the longitudinal axis of the handle, the magnet 5 may be made of desirably large diameter without undue enlargement of the confining handle. As the magneto parts are all supported by the side plate 11 only of the frame, these parts are retained in assembled position even when the casing 4 and the side plate 12 have been removed. The gaps between the magnet 5 and the adjacent pole faces may be readily varied to produce operation of the magneto at maximum efficiency, by virtue of the slotted openings 32 and the clamping bolts 31, 42 associated therewith, and rapid access to the interior of the handle may be effected by merely releasing one of the clamping nuts 22 and by subsequent removal of one or both of the sections of the casing 4. The casing 4 normally completely encloses the frame, the magneto and the actuating gearing and presents an extremely neat appearance with only the rear clamping nuts 22 visible. A majority of the elements of the structure may be formed of sheet metal with the aid of punches and dies, thereby reducing the cost of construction to a minimum. The entire structure may be readily assembled or dismantled with the aid of ordinary tools, and the relative simplicity of

the device enables effective operation thereof by a novice.

It should be understood that it is not desired to limit the invention to the exact details of construction and to the precise mode of operation herein shown and described, for various modifications within the scope of the claims may occur to persons skilled in the art.

It is claimed and desired to secure by Letters Patent:—

1. In a flash light, a lamp support having a flange, a frame associated with said support, a magneto carried by said frame, a casing comprising sections interlocking at one end with said flange, means for operating said magneto from the exterior of said casing, and a single clamping member for rigidly uniting the sections of said casing at the opposite end thereof.

2. In a flash light, a lamp support having a rearwardly projecting annular flange, a lamp associated with one side of said support, means associated with the other side of said support for lighting said lamp, and a longitudinally divided sectional casing providing a handle and an enclosure for said lighting means, the front portions of the casing sections interlocking with said flange and the rear portions thereof being united by a single connecting bolt.

3. In a flash light, a lamp support, a lamp associated with the front of said support, a pair of laterally spaced side plates detachably associated with the rear of said support, a magneto carried by and between said plates, a sectional casing enclosing said plates, and a single member for simultaneously uniting the sections of said casing and maintaining said plates in spaced relation.

4. In a flash light, a lamp support, a lamp associated with the front of said support, a pair of laterally spaced side frames secured to the rear of said support, a magneto mounted in the rear of the space between said frames, an oscillatory lever for actuating said magneto pivotally associated with said frames between said magneto and said support, and a sectional casing coacting with said support and enclosing said frames and said magneto, the sections of said casing coacting along a plane passing longitudinally through said space and providing a handle disposed coaxial with said lamp, and said lever being movable laterally of the handle axis.

5. In a flash light, a lamp support, a frame associated with said support, a magneto carried by said frame, a casing comprising sections interlocking at one end with said support, means for operating said magneto from the exterior of said casing, and a single clamping member for rigidly uniting the sections of said casing at the opposite end thereof.

6. In a flash light, a lamp support, a lamp associated with said support, means associated with said support for lighting said lamp, and a longitudinally divided sectional casing providing a handle and an enclosure for said lighting means, the front portions of the casing sections interlocking with said support and the rear portions thereof being united by a single connecting member.

16 7. In a flash light, a lamp support, a lamp carried by said support, a pair of laterally spaced plates forming a frame secured to said support, a magneto disposed between said plates, a sectional casing enclosing said plates and said magneto, and a single member uniting the sections of said casing, said member coacting with said frame to maintain the plates thereof in proper spaced relation.

20 8. In a flash light, a lamp support, a lamp carried by said support, a pair of spaced side frames secured to said support, a magneto mounted at the rear of the space between said frames, mechanism for actuating said magneto located in said space between said support and said magneto, and a sectional casing enclosing said frames and said magneto, the opposite ends of said casing being detachably secured to said support and to said frames respectively.

25 30 In testimony whereof, the signature of the inventor is affixed hereto.
